UNITED STATES PATENT OFFICE.

JAY B. LAMPMAN AND AUGUST KITTELBERGER, OF NEW YORK, N. Y., ASSIGNEES TO INTERNATIONAL STEAM PUMP COMPANY, OF NEW YORK, N. Y., A CORPORATION OF NEW JERSEY.

AIR-COMPRESSOR.

No. 926,124.

Specification of Letters Patent.

Patented June 29, 1909.

Application filed June 20, 1908. Serial No. 322,510.

To all whom it may concern:

Be it known that we, JAY B. LAMPMAN and AUGUST KITTELBERGER, citizens of the United States, both residing in the city of New York, county of Kings, and State of New York, have invented certain new and useful Improvements in Air-Compressors, fully described and represented in the following specification and the accompanying drawings, forming a part of the same.

This invention relates to a device for relieving the compressor cylinder of any air which may enter the cylinder by leakage, or otherwise, when the compressor cylinder is unloaded by unloading devices that prevent or reduce the admission of air at the inlet.

The invention is especially applicable in connection with multi-stage air compressors, but may be used also in single stage compressors.

In two-stage air compressors, when an unloading device is used by which the inlet to the low pressure cylinder is closed, or an unloading device of any other type by which the inlet admission and pressure are reduced, any air entering the high pressure cylinder must be compressed from a low initial pressure to the full discharge pressure, thus causing excessive heat, and the same difficulty exists in single cylinder compressors operating with such unloading devices.

The object of the present invention is to provide a simple and efficient device by which such air in the cylinder may be discharged at or near atmospheric pressure, when the compressor is unloaded.

In the accompanying drawings forming a part of this specification, the invention is shown as applied in its preferred form to a two stage air compressor employing an unloading device of the suction throttling type, and this construction will now be described in detail and the features forming the invention then specifically pointed out in the claims.

In the drawings—Figure 1 is a diagrammatic elevation of the compressor. Fig. 2 is a longitudinal section of the high pressure cylinder with the relief device. Fig. 3 is a detail section of the relief device on an enlarged scale.

Referring to said drawings, A is the low pressure cylinder having the suction B and delivery C, D is the intercooler, E the suction pipe from intercooler D to high pressure

cylinder F, and G the high pressure cylinder delivery. The low pressure cylinder is shown as equipped with a suction throttling device H, which may be of any suitable form, being illustrated as the well-known Erie unloading device, which is controlled from the high pressure delivery or receiver through pipe 20 so as to close the suction throttling valve and prevent suction fluid entering the low pressure cylinder, when the pressure in the receiver rises to the point for which the unloading device is set. The high pressure cylinder, as shown in Fig. 2, is provided with the well-known Cincinnati air valve gear having the mechanically actuated suction and delivery valves a at opposite ends of the cylinder, with automatic puppet valves b controlling the discharge outside the mechanically actuated valves, 10 being the suction and 11 the delivery passages of the compressor.

All the parts thus far described may be of any suitable construction, and this special type of compressor and unloading device is selected only for purpose of illustration.

Referring now to the relief device embodying the present invention, this device is exactly the same at opposite ends of the cylinder F, so that a single description and the same references may be used for both devices. The discharge port is connected inside the puppet valves b, to a port 1 passing through the cylinder head and normally closed by a valve c. This valve c opens the port 1 to a chamber 12 connected to the atmosphere through a port 2 controlled by a spring pressed puppet valve d the spring pressure of which is preferably made adjustable by a set screw 3, as usual in such constructions, the puppet valve chamber connecting by outlet 13 to the atmosphere or muffler, as may be convenient. The valve c is carried by a stem 4 on which is a piston 5 working in chamber 6 and spring pressed outward by spring 7 so that the spring pressure tends to open the valve c and connect the cylinder discharge passage to chamber 12. The space in chamber 6 outside the piston 5 is connected by pipe 14 to the intercooler D and chamber 6 on the opposite side of piston 5 is provided with an opening 8 to the atmosphere.

The operation of the device is as follows:—When the throttling unloading device H is open and the compressor is run normally,

the pressure in intercooler D operating through the pipe 14 upon the outer side of piston 5 is sufficient to hold valve c to its seat and close the port 1 so that the valve c is not opened by the discharge pressure of the high pressure cylinder. When the throttling valve of unloading device H closes the suction of cylinder A, the intercooler pressure is reduced to some point below atmospheric pressure, and the pressure outside piston 5 becomes less than the pressure in chamber 6 inside the piston 5, which inside pressure is that of the atmosphere on account of the opening 8. The piston 5 is then moved outward by the unbalanced pressure, aided by the spring 7, in the construction shown, thus opening the valve c, so that any air in the cylinder F will at each movement of the piston be forced out through port 1, chamber 12 and port 2 to the atmosphere outlet 13, the relief valve d being set so as to open under a light pressure. When the pressure in the receiver is reduced and the suction throttling device H operates to open the suction valve of cylinder A, the pressure in the intercooler D rises again and returns piston 5 to normal position, thus closing the valve c for the normal operation of the compressor.

It will be understood that the relief valve d may be omitted, if the valve c be arranged to close to prevent the back flow of air into the cylinder, but preferably the valve c remains open when the intercooler pressure is reduced, and the relief valve d is used. The intercooler pressure on piston 5 may be resisted by a spring and the atmosphere, as shown, or by either springs or the atmosphere alone, or springs tending to close the valve may be used to form a relief valve opening under light pressure on the discharge stroke when the compressor is unloaded and closing on the suction stroke to prevent back flow of air, according to the intercooler pressure conditions. It is not essential that the intercooler pressure shall drop to atmospheric, when the compressor is unloaded, the only essential being that the difference between the intercooler pressure when unloaded and loaded, shall be sufficient to operate the valve c.

If the device be applied with single stage compressors, fitted with unloading devices of the suction throttling type, the chamber 6 outside the piston 5, will be connected to the suction port inside the throttling valve, and the action is the same as above described, the proportioning of the piston and valves, and the arrangement of springs, being such as to cause the valve to remain closed when the pressure in the suction port is at or near normal pressure, and permitting the valve to open when the predetermined drop in the pressure in the suction port occurs, through closing of the suction throttling device.

It will be understood that the invention is not limited to use with unloading devices of the suction throttling type, but that it is applicable, also, in connection with other types of unloading devices in connection with which the cylinder is to be relieved from leakage air when unloaded by throttling the suction or otherwise preventing the admission of suction fluid.

What is claimed is:—

1. The combination with an air or gas compressor having an unloading device by which the inlet pressure is reduced when the compressor is unloaded, of an outlet valve opening to the atmosphere, a piston controlling the outlet valve, and means for applying inlet pressure to said piston to normally close the valve and permit the valve to open when the compressor is unloaded. 75
2. The combination with an air or gas compressor having an unloading device by which the inlet pressure is reduced when the compressor is unloaded, of an outlet valve opening to the atmosphere, a piston controlling the outlet valve, means for applying inlet pressure to said piston to normally close the valve and permit the valve to open when the compressor is unloaded, and an automatic valve outside said outlet valve to prevent the back flow of air into the cylinder. 85
3. The combination with a multi-stage air or gas compressor having an unloading device by which the inlet pressure of the high pressure cylinder is reduced when the compressor is unloaded, of outlet valves on the high pressure cylinder opening to the atmosphere, and pistons operating said outlet valves and subjected to intercooler pressure to normally close said valves and permit the valves to open when the compressor is unloaded. 95
4. The combination with a multi-stage air or gas compressor having an unloading device by which the inlet pressure of the high pressure cylinder is reduced when the compressor is unloaded, of outlet valves on the high pressure cylinder opening to the atmosphere, pistons operating said outlet valves and subjected to intercooler pressure to normally close said valves and permit the valves to open when the compressor is unloaded, and automatic valves outside the outlet valves to prevent the back flow of air into the cylinder. 100
5. The combination with an air or gas compressor having an unloading device by which the inlet pressure is reduced when the compressor is unloaded, of an outlet valve opening to the atmosphere, a piston controlling the outlet valve, and means for applying inlet pressure to one side of said piston to close said outlet valve, said piston being subjected to pressure on the opposite side to open said outlet valve when the compressor is unloaded. 110

6. The combination with a multi-stage air or gas compressor having an unloading device by which the inlet pressure of the high pressure cylinder is reduced when the compressor is unloaded, of outlet valves on the high pressure cylinder opening to the atmosphere, pistons operating said outlet valves, and means for applying intercooler pressure to said pistons to close said outlet valves, 5 said pistons being subjected to pressure on the opposite sides to open said outlet valves when the compressor is unloaded.
- 10 7. The combination with a multi-stage air or gas compressor, of a suction throttling device on the low pressure cylinder controlled 15 by the receiver pressure to throttle the suction and unload the compressor, and outlet

valves on the high pressure cylinder opening to the atmosphere, pistons operating said outlet valves and actuated to close the valves 20 by intercooler pressure and subjected to pressure on the opposite side to open said outlet valves when the compressor is unloaded, and automatic valves outside said outlet valves to prevent the back flow of air 25 into the cylinder.

In testimony whereof, we have hereunto set our hands in the presence of two subscribing witnesses.
